Primary Examiner — Sandra S Snapp*Assistant Examiner* — Katherine Glennon(74) *Attorney, Agent, or Firm* — Ladas & Parry, LLP(57) **CLAIM**

The ornamental design for a wrist guard, as shown and described.

DESCRIPTION

FIG. 1 is a perspective view of a wrist guard showing the claimed design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom view thereof.

The broken lines depict portions of the wrist guard that form no part of the claimed design.
